Charles Lane Bingham Massachusetts
Letters Patent

The Schedule referred to in these Letters Patent and making part of the same containing a description in the words of the said Charles Lane himself of his improvement in the fireplace and Grate for burning Wood and Coal.

To all people to whom these presents shall come. BE it known that of Charles Lane of Bingham in the County of Plymouth and Commonwealth of Massachusetts Esquire. have invented a new and useful improvement in the construction of a fireplace & Grate for burning Wood and Coal. and that the following is a full and accurate description thereof. — (The external form of the fireplace is the same as in common use. (Fig. 1.) The bottom of the fireplace is formed by a iron Grate laid horizontally below the level of the hearth (Fig. II. A) Front bars are inserted (Fig. 1.) and their lower part rests upon the upper plate of the ash pan known after described. The ends of the front bars are inserted in grooves of iron placed perpendicular & formed in plates which run to the back of the fireplace. the exterior surface of these plates is fluted and they together with the floor of the hearth at the ends of the horizontal grates before mentioned. — the jambz — the back of the fireplace — the plates in front continued from the ends of — the front bars to the jambz and horizontal plates above form air channels at both ends of the grates which are generators of hot air. On these generators metal pots are inserted designed to contain water to be converted into vapour by the heat and transmitted from thence by tubes behind the jambz & through any part of the mantel piece to the room. the object of this vapour is to moisten the air of the room (see Fig. II Generators marked B. vapour tubes C. water pots D.) Hot air from the generator is transmitted to the room by tubes inserted through the

sides thereof into the furnace and thence through solid bed of clay to the room in such place as may be most convenient (Fig. II. D.) the pots containing water may be covered and surmounted by ornamental masonry with tops containing a lateral aperture, ^{in each} so moveable as to regulate the transmission of vapour (Fig. I. A.) The draft of air to keep the wood or coal ignited is received from below the hearth through a horizontal tube closed at the inner end and opened by a register or air valve at the outer end. With this main tube other tubes are connected which are placed horizontally & at right angles thereto to conduct and distribute the air beneath & to the back part of the grate. The draft may be increased or diminished by a moveable register or air valve before mentioned which can be raised or lowered by a metal chain attached to a wheel with a knob (valve & tube Fig. II. E. & wheel and knob Fig. II. G.) A stationary ash pan covered with a fine grate is placed in the hearth the top of which is level therewith to receive all the ashes which fall from the grate. This fine grate is moveable & when taken up the ashes in the pan may be emptied therefrom into a pit beneath through an aperture in the side of the pan (Fig. II. ash pan No. side aperture I.)

What I claim as my own invention and not previously known or the above described improvement is, First, the sinking of the grate below the level of the hearth, by which means ignition sooner takes place and combustion is increased by excluding the coal from the external air from the Room & the convenience resulting by the deposit of ashes in the bottom of the grate - Second, the generator of hot air & the mode of emitting it to the room - Third, The production of vapour from the pot of water aforesaid & the transmission of the vapour to the Room to minister the air - 4th the valve beneath the hearth and the pipes connecting therewith, by which the draft of air may be increased or diminished as directed - Fifth, The ash pan upon the plan described as before mentioned.
